EARRING RETAINER

Roberta M. Gould, New York, N. Y.

Application May 22, 1934, Serial No. 726,944

4 Claims. (Cl. 63—14)

This invention relates to an improvement in ear-ring retainers, and has for its object to provide a simple, inexpensive and effective device for holding ear-rings in position on the lobes of the ears and preventing slippage of the ear-rings therefrom.

The conventional type of ear-ring widely used at the present time, is held on the lobe of the ear by being clamped thereon, the vogue of piercing the ears to accommodate an ear-ring having since passed. The present day type of ear-ring is provided with a yoke which straddles the lobe of the ear, and has a clamping screw formed with a rounded end or head movable in the yoke, to clamp the lobe. In order to securely hold the ear-ring in position on the ear, it is necessary that the clamping screw be tightened to a considerable extent with the result that the pressure imposed on the lobe of the ear often causes discomfort. On the other hand, if the clamping screw is insufficiently tightened to securely clamp the lobe, the ear-ring will fall off and be lost. This is particularly true in warm weather when perspiration induces a slippery condition of the skin and it is almost impossible to hold an ear-ring in place without tightening the clamping screw so that the pressure on the ear lobe is uncomfortably severe.

The primary object of this invention is to provide a simple, unobtrusive pad which is adhesively attached to the back of the ear lobe, and against which the head of the clamping screw impinges. This pad not only relieves the pressure of the screw on the ear, but is provided with a recess or seat for the end of the screw so that slippage of the ear-ring is effectively prevented and at the same time, the pressure of the clamping screw may be lessened.

In the accompanying drawing, wherein several embodiments of the invention are shown, Fig. 1 is a sectional view of the improved retainer, showing the reception of the ear-ring thereby; Fig. 2 is a face view of one of the retainers applied to the back of the ear-lobe; Fig. 3 is a perspective view of the retainer; Fig. 4 is a perspective view of a modified device; and Fig. 5 is a sectional view of the device shown in Fig. 4, as applied to the ear.

Referring to the structure shown in Figs. 1 to 3, 5 indicates the yoke which forms part of the ear-ring structure. At one end the yoke carries an ornament 6 or the like. With some types of ear-rings, the ornament is dependent from the yoke, but since the ear-ring structure forms no part of the invention, its precise structure is immaterial. A threaded clamping screw 7 is mount-

ed in one end of the yoke, said screw being provided with a rounded head or end 8 which cooperates with a fixed stop 9 on the other end of the yoke, to clamp the ear-ring on the lobe 19 of the ear.

The improved retainer is shown in detail in Figs. 2 and 3, where it will be seen that it is provided with a base or body portion 10 of disk-shape which has an exposed adhesive-surfaced face 11 adapted to be applied against the back of the ear lobe 19, as clearly shown in Figs. 1 and 2. United with the body portion 10 is an annulus 14, which by reason of its annular form, defines a recess or pocket 12 into which the head or end 8 of the clamping screw fits. The body portion 10 and the united annulus 14 are both made of soft textile fabric and the pressure of the head of the clamping screw imposed upon the body portion 10 is accordingly well cushioned. The head of the clamping screw being pocketed in the recess 12 is prevented from lateral movement and consequently the ear-ring cannot easily be displaced and fall off.

In the modified structure shown in Figs. 4 and 5, the body portion 10 is dispensed with and the entire device consists of the annular member 14 which has one of its faces coated with the adhesive. With this device, the head 8 of the clamping screw lies in the center opening 15 of the annulus and impinges directly against the ear lobe and is prevented from lateral slipping by its confinement in the recess or central opening 15.

In use, the device is simply adhesively applied on the back of the ear lobe. The ear-ring then has its clamping screw tightened until the head 8 thereon seats within the recess of the device with comfortable pressure on the ear. Slipping of the ear-ring will be effectively prevented with the imposition of a relatively light pressure by the clamping screw.

What I claim is:

1. A device of the class described comprising the combination of an ear-ring provided with a clamping screw, and a pad provided with an adhesive surface for application on the ear lobe, said pad receiving the pressure of the clamping screw of the ear-ring.
2. A device of the class described comprising the combination of an ear-ring having a clamping screw, and a pad provided with an adhesive surface for application on the ear lobe, said pad receiving the pressure of the end of a clamping screw of the ear-ring, said pad being provided

with a recess in which the end of the clamping screw fits.

3. A device of the class described comprising an ear-ring clamping member, a pad having an 5 annular wall defining a central recess into which the end of the ear-ring clamping member fits, and an adhesive coating applied to one face of said pad to attach the pad to the ear.

4. In combination an ear-ring having a clamping screw, and a pad having an adhesive coating on one of its faces by which it is adhesively attached to the ear and having a recess forming a seating for the end of the ear-ring clamping screw. 80
